UNITED STATES PATENT OFFICE

STANLEY W. HAYES, OF RICHMOND, INDIANA, ASSIGNOR TO HAYES TRACK APPLIANCE COMPANY, OF RICHMOND, INDIANA, A CORPORATION OF INDIANA

BUMPER POST

Application filed September 5, 1929. Serial No. 390,477.

The invention relates to a bumper post of the type in which a bumper head located between the rails is supported from the roadbed by divergent compression members and by tension members secured to the roadbed at points in advance of the head. In such bumpers the principal problem is to deal effectively with that part of the shock of impact which is transmitted as tension, and the mode of attachment of the tension members to the roadbed, which term is used broadly to indicate the ballast, ties, rails, track fixtures, or any of them, is recognized as of cardinal importance. The present invention is a simple solution of this problem. It consists in structural features described in the specification and pointed out in the claims.

Referring to the drawings: Fig. 1 is a perspective of the bumper post.

Fig. 2 is a plan.

Fig. 3 a detail end elevation on a larger scale, showing the mode of connection of the tension member to the track.

Fig. 4 is a section on the line IV—IV,

Fig. 3.

Fig. 5 is a section on the line V—V, Fig. 3.

Fig. 6 is a perspective view of one of the tension bars.

Fig. 7 is a detail bottom perspective of part of a tension fixture.

Fig. 8 is a rear elevation, partly in section, showing the bumper head and the mode of connection thereto of the tension members and compression members.

Fig. 9 is a side view of the bumper head showing the seat for the tension member.

Fig. 10 is a detail side elevation showing the compression track fixture and the lower end of the compression member seating therein.

Fig. 11 is a plan corresponding to Fig. 10.

Fig. 12 is a section in the line XII—XII, Fig. 10, and

Fig. 13 is a section in the line XIII—XIII, Fig. 10.

In the illustrated bumper post, 1 is the bumper head and 2 are the compression members shown as angle irons connected to the bumper head and secured to the roadbed by compression track fixtures 3 of suitable form

which are preferably connected both to the rails and to the ties. Various modes of attachment of the track fixtures to the road bed may be adopted, but, in that illustrated, the compression fixtures are bolted to the rail webs at 4 and spiked at 5 to adjacent ties on which they seat and the space between which they span. Each angle 2 seats within and is bolted to upstanding annular wall structure 6 of the corresponding track fixture 3, which has, within and at the base of said wall structure, a series of aligned studs 7, the tops of which, being in the same plane, constitute a seat for the bottom of the wide side of the angle which side also seats between the slightly projecting portions 8 of the wall adjacent the studs and the opposed inclined sides of studs 9 staggered with respect to the studs 7. Avoidance of extended continuous contact surfaces obviates the necessity of specially finishing the associated parts and makes it easier to assemble them. The bottom edge of the narrow side of the angle rests on the continuous seat 10. As in the bumper post of my Patent No. 1,705,479, March 19, 1929 this track fixture may have tie face abutting shoulders 11, anchor bar slot 12, anchor bars 13, and connecting brace rod 14.

Stress of impact is further transmitted, as 80 tension, from the bumper head 1 by tension members 15, shown as bars whose upper ends seat in the side faces of the head, in channels 16 of the same cross section and shape as the bar ends, each of which is best formed as a 85 hook 17 projecting straight forward in a plane parallel to the track. Release of the connection of the tension bar to the bumper head by relative endwise movement of the channel and the end of the tension bar seating 90 therein is prevented by the corresponding cross lug 18 and groove 19 formed respectively in the side wall of the channel 16 and in the upper side of the hook end 17. The upper end of each compression angle 2 over- 95 laps and closes the open side of the adjacent tension-member-receiving channel and is fastened to the head and made to seat against its side face and against the exposed side of the hook 17 by bolts 20 thus securing both com- 100

pression and tension members to the head by the same means. This novel arrangement is simple and effective but not exclusive of other modes of connection of either or both tension and compression members. These tension members 15 which are shown as bars, diverge from the head to points in advance of it, opposite to each other in the track, and adjacent the bases of the respective rails where the members deliver stress of impact to a metallic cross bar 21, properly positioned in the track, which extends across the track substantially in the plane of the ties and seats beneath the bases of the respective rails. The tension members 15 embrace the metallic cross bar which in the structure illustrated passes through a closed loop 22 or hole in the front end of each tension member by which it is completely enclosed. This is far more secure than an open hook embracing the cross bar without entirely enclosing it and requires no fastening bolts or other structure to be set up at the time of installation to preclude possibility of the hook straightening out under impact. The tension member is shown as a bar having its lower end bent into a closed loop with the end of the bar welded to its body at 23, but it will be apparent that the end of the tension member need not be bent to form the hole, but that a hole may be made through the material constituting the end of the tension member. Where the tension member is a bar having its end looped back on itself, it may be bent either forward or backward so that the body of the bar may pass over and in front of, instead of behind and under the metallic cross member. Angular spacer clips 24 are secured to the metallic cross member just inside the loops 22 of the tension members to oppose their tendency to be drawn toward each other on bumper head impact. The preferred means for positioning the ends of the metallic cross member opposite each other in the track and for maintaining the bar in the desired position are those illustrated, i. e. the tension track fixtures 25, each of which bears against the web of the rail, is bolted thereto at 26 and spiked at 27 to adjacent ties on which it seats, although it may be clamped to the rails only. Each of these track fixtures has means for supporting the metallic cross bar and aligning it crosswise of the track. In the construction shown this is a recess or socket 28 formed in the body of the tension track fixture and extending endwise from its outside through the track fixture and downward from the plane of the underside of the track rail base to a point sufficiently below the base of the inverted cross rail to support it adequately by shoulders at each side of the recess. The track fixtures themselves might extend under the bases of the rail so that the seating of the metallic cross member on the underside of the rails would be indirect. The

shape of the socket depends on the nature and cross section of the metallic cross member, which may be, as here illustrated, an inverted 60-lb. or heavier A. S. C. E. rail. Where the shape of the cross bar admits, metal may be economized and weight reduced by making the socket 28 less than a complete enclosure of the metallic cross bar, but this is a matter of choice. The term metallic cross bar is intended to be broad enough to include composite structures made up of a plurality of bars or otherwise built up, but a single inverted track rail or an I beam is preferred. 70 75

I claim:

1. A bumper post having a bumper head, 80 diverging struts transmitting thrust of impact from the head to the roadbed, a metallic cross bar between the ties extending across the track beneath the rails in substantially the plane of the track, means for securing 85 said cross bar to the rails, and tension members secured to the bumper head and diverging therefrom to points below and adjacent the respective rail bases and there opposing themselves to the underside and front of the 90 cross bar to deliver stress of bumper impact thereto.

2. A bumper post having a bumper head, 95 diverging struts transmitting thrust of impact from the head to the roadbed, a metallic cross bar between the ties extending across the track beneath the rails in substantially the plane of the track, tension members extending downward, outward and forward from the bumper head to points below and 100 adjacent the respective rail bases and there having holes through which end portions of said cross bar extend, and means for preventing movement of the cross bar-receiving ends of the tension members toward each other 105 under bumper impact.

3. A bumper post having a bumper head, 110 diverging struts transmitting thrust of impact from the head to the roadbed, a metallic cross bar between the ties extending across the track beneath the rails in substantially 115 the plane of the track, tension track fixtures located opposite each other in the track and provided with cross bar supporting means extending under structure of the metallic cross bar, and tension members secured to the bumper head and diverging therefrom to points below and adjacent the respective rail bases and there receiving the cross bar to deliver thrust of bumper impact thereto. 120

4. A bumper post having a bumper head between the rails, divergent struts bearing on the respective rails for transmitting thrust of impact from the bumper head to the roadbed, a metallic cross bar extending across 125 the track beneath the rails, secured thereto, and seating on the underside of the base of the rails, and tension bars extending downward, outward and forward from the bumper head to points adjacent the bases of the re- 130

spective rails and there having a closed loop or hole receiving the cross bar structure.

5. A bumper post having a bumper head between the rails, divergent struts secured thereto and to the roadbed for transmitting thrust of impact from the bumper head, a metallic cross bar extending across the track, secured to the roadbed and seating under the respective rail bases, means for positioning 10 the end of the metallic cross bar, tension members secured to the bumper head, diverging therefrom to points adjacent the bases of the respective rails and there receiving and surrounding the metallic cross bar.

15. A bumper post having a bumper head, compression members for transmitting thrust of impact from the head to the roadbed, tension members secured to the bumper head and diverging therefrom to points adjacent 20 and below the bases of the respective rails, where each is provided with a hole, and a metallic cross bar extending through said holes in the tension members, secured to the rails and seating beneath their respective bases.

25. A bumper post, as set forth in claim 6, having means carried by the cross bar for preventing movement of the front ends of the tension members toward each other.

30. A bumper post having a bumper head, means for transmitting thrust of impact from the head to the roadbed, tension track fixtures located opposite each other in the track and secured to the rails, a metallic cross bar 35 located substantially in the plane of the ties, cross-connecting said fixtures and extending beneath the rail bases, said track fixtures having means for positioning the respective ends of the cross bar, and tension members 40 secured to the bumper head and diverging therefrom to points adjacent the respective rail bases and there encircling said cross bar.

45. In a bumper post a tension track fixture having a flange portion adapted to be secured to the rail and a base portion having a cross bar receiving and supporting socket exterior to the rail base.

50. In a bumper post a tension track fixture having a rail flange receiving portion and a body portion provided with a transversely extending cross bar receiving open-ended socket exterior to the rail flange-receiving portion of the track fixture and located to have its top in the plane of the rail base, 55 and a flange for attachment of the fixture to the rail web.

60. A bumper post having a bumper head, tension members seating in said head and connected to the roadbed structure adjacent the respective rails in advance of said head, and compression members outside the upper ends of the tension members and holding said members to their seats.

65. A bumper post having a bumper head provided at each side with open sided grooves

for receiving the ends of tension members, tension members having their upper ends seated in said grooves and their lower ends secured to the roadbed at opposite points of the track, and compression members whose upper ends close the open side of said grooves and which diverge from the bumper head to opposite points in the track, and means for securing the upper ends of said compression members to the head and thereby maintaining 70 the upper ends of the tension members in place.

13. A bumper post having a bumper head, tension members seating in said head at opposite sides thereof and extending to the track adjacent the respective rails, and compression members having their upper ends exterior to the upper ends of the tension members to hold them in place, and fastening 80 means securing the upper ends of both in 85 place.

14. A bumper post having a bumper head between the rails, and compression members and tension members extending therefrom to the track, said bumper head having in its 90 sides outwardly facing grooves, and said tension members having hooks at their upper ends opening forwardly, seating in said grooves and insertable into them sidewise without endwise movement and secured at 95 their lower ends adjacent the rails to the road bed.

15. A bumper post having a bumper head, means for transmitting thrust of impact from the head to the track, a pair of tension 100 members secured to the bumper head and to the track and having their upper ends formed as hooks seating in the sides of the bumper head and extending straight forward lengthwise of the track.

16. In a bumper post, a compression track fixture having an upstanding angular wall portion, and seats adjacent the same for angularly related sides of the compression member, the seat for the bottom of one of 110 said sides being made up of spaced aligned lugs.

17. A bumper post having a bumper head between the rails, divergent struts secured thereto and to the roadbed for transmitting thrust from the bumper head, an aligned metallic cross bar seated beneath the rail bases in substantially the plane of the track, and tension transmitting structure including means receiving and surrounding the cross bar at points opposite each other in the track and adjacent the respective rails, and means placing such cross bar receiving and surrounding means in connection with the bumper head to transmit stress of impact 120 therefrom to the cross bar.

18. A bumper post having a bumper head, compression members for transmitting thrust of impact from the head to the roadbed, a metallic cross bar seating beneath the rail 125

bases in substantially the plane of the track, tension track fixtures secured to the roadbed at points opposite each other in the track and provided with means receiving, aligning and supporting said bar, and tension bars transmitting stress of impact from the bumper head to the cross bar and rails at points adjacent the rails at the inside of the rails.

- 10 19. A bumper post having a bumper head, means for transmitting thrust of impact from the bumper head to the roadbed, including tension track fixtures located opposite each other in the track and secured to the roadbed, a metallic cross bar located substantially in the plane of the ties and extending under the rail bases, said tension track fixture being provided with cross bar receiving and supporting means extending below the rail base and underlying metallic cross bar structure.

In testimony whereof, I have signed this specification.

STANLEY W. HAYES.
